[57] CLAIM

The ornamental design for the oil filter mounting
bracket, substantially as shown and described.

DESCRIPTION

FIG. 1 is a perspective view of an oil filter mounting
bracket, showing my new design;

FIG. 2 is a front elevation thereof;

FIG. 3 is a right side elevation thereof;

FIG. 4 is a rear elevational view thereof;

FIG. 5 is a top plan view thereof; and

FIG. 6 is a bottom plan view thereof.
